INVENTOR:

William Roemer,

BY Drake & Co ATTY'S.

UNITED STATES PATENT OFFICE.

WILLIAM ROEMER, OF NEWARK, NEW JERSEY.

BAG-FASTENER.

SPECIFICATION forming part of Letters Patent No. 398,542, dated February 26, 1889.

Application filed September 7, 1888, Serial No. 284,787. (Model.)

To all whom it may concern:

Be it known that I, WILLIAM ROEMER, a citizen of the United States, residing at Newark, in the county of Essex and State of New Jersey, have invented certain new and useful Improvements in Bag-Fasteners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a lock-catch or fastening-slide for bag-frames, satchels, and similar articles of a reduced cost of construction, of greater simplicity and strength, and one that can be applied readily and easily to said bag-frames; and it consists in the improved catch having the combinations and arrangements of parts substantially as will be hereinafter set forth, and finally embodied in the clauses of the claim.

Referring to the accompanying drawings, in which like letters of reference indicate corresponding parts in each of the several figures, Figure 1 is a plan of a satchel embracing my improvements. Fig. 2 is a plan of a catch in detail, indicating the same in its closed or catching relation to the hook of the opposite jaw of the frame. Fig. 3 is a similar plan, showing the same in disengagement with said hook. Fig. 4 is a section taken on line *x* of Fig. 2, and Fig. 5 is a section taken on line *y* of Fig. 3. Fig. 6 is a detail side elevation of the improved catch, and Fig. 7 is a section of the same, taken on line *y'*. Fig. 8 is a detail plan of the slide, and Fig. 9 is a detail side elevation of the same, and Fig. 10 is a sectional view taken on line *z*. Fig. 11 is a plan of a face-plate. Fig. 12 is a detail side elevation of a spring which I prefer to employ. Fig. 13 is a detail side elevation of a box or case adapted to retain the spring in position, and at the same time hold down the slide in proper relation to the face-plate and hook; and Fig. 14 is a modification of the device. Fig. 15 is a sectional view taken on line *x'*, Fig. 14.

In said drawings, *a* indicates a suitable bag, case, satchel, or other similar article having ordinary jaws, *b*, adapted to be fastened together to close the bag.

c, Fig. 11, indicates a face-plate, having therein a slot, *c'*, adapted to allow the passage of a catching-tongue, *d'*, of a catch or slide, *d*, to pass downwardly therethrough toward the co-operating tongue *e*, (indicated in outline in Figs. 2 and 3 and shown in side elevation in Fig. 6,) the said catching-tongue passing down through the upper or outer jaw, *b*, of the frame, and thus engages the said tongue *e*, lying thereunder, in any suitable manner. The said face-plate *c* is secured upon the upper face of the said jaw *b* by means of the fastening-lugs *f*, Fig. 13, of the box *d*, the said lugs extending downward from the lower edge of said box and passing through suitable perforations in the face-plate and through suitable perforations in the bag-frame *b*, the said lugs being clinched on the under side of the said jaw in any suitable way to hold the parts together, as will be understood.

The box or case *d* is preferably an oblong piece of sheet metal pressed or shaped to form a spring-chamber, *d'*, Figs. 4, 5, and 7, adapted to hold the spring *h* in place, as indicated. The lower lateral edges of said box are notched, as at *d'*, Fig. 13, to allow of a longitudinal movement of the sliding catch, whereby the catching-tongue of said slide is thrown from its fastening to its unfastening position. The said slide (shown more clearly in Figs. 8, 9, and 10) consists of a cross-bar, *i*, adapted to pass through the notch *d'* in the box, at the ends of which are arranged finger-pieces *i'*, which lie against the outer side of the box *d*, as indicated in Figs. 2, 3, 6, and 7.

At the center of the cross-bar, preferably formed integral therewith, is the catching-tongue *d'*, above referred to, and on the upper side of the cross-bar are formed inclines *j*, adapted to provide suitable bearings for the spring *h*, which latter is bent to form co-operating inclines *h'*, which bear on the cross-bar and hold the same in its fastened or unfastened position.

By moving the slide from one side of the angle in the spring to the other the catching-tongue *d'* will be brought into fastening engagement with the hook *e* or be released therefrom, as will be understood.

I do not wish to be understood as limiting myself to the exact arrangement of parts shown, as various changes may be made with-

out departing from the spirit of the invention—as, for example, a spiral spring may be employed in lieu of the one first described, as indicated in Fig. 14; but the flat spring having opposite inclines forming an angle is the one preferred.

Having thus described the invention, what I claim as new is—

1. The improved satchel-catch combining a face-plate adapted to be secured to the frame of the bag or satchel, a box secured on said face-plate and containing a spring, and a slide arranged between the face-plate and box and free to be thrown by the fingers from an uncatching to a catching position, and having a catching-tongue adapted to engage with a co-operating catch on the bag-frame, substantially as and for the purposes set forth.

2. In combination, a face-plate having a slot, c' , for the catching-tongue to work in, and perforations g for fastening-lugs, a box, d^2 , containing a spring and having said fastening-lugs arranged to pass through said perforations, and having on the under side a notch, d^4 , adapted to receive and allow a slide to work therein, and said slide consisting of a cross-bar arranged in the said notch, a catching-tongue extending through the slot c' to engage with a co-operating catch, and finger-pieces arranged at the ends of the cross-bar on the

outside of the box, the said spring bearing on said cross-bar and against the inner walls of the box, all substantially as and for the purposes set forth.

3. The combination, with the slotted face-plate c and a box having a notch, a^4 , of a slide held in said notch and having a depending catching-tongue projecting through the slot of the face-plate to engage a co-operating catch, and a spring held in said box and bearing on said slide, said parts being arranged and combined substantially as and for the purposes set forth.

4. In combination, a box forming a spring-chamber, d^3 , and having notches to receive a slide, a slide arranged in said notches and having a catching-tongue to engage a co-operating catch of the bag-frame, said slide having finger-pieces or parts lying on the opposite sides of said box, and a spring arranged in said box and bearing on said slide, substantially as and for the purposes set forth.

In testimony that I claim the foregoing I have hereunto set my hand this 6th day of September, 1888.

WILLIAM ROEMER.

Witnesses:

CHARLES H. PELL,
E. L. SHERMAN.
